UNITED STATES PATENT OFFICE.

JOHN L. BERGLUND, OF BRIDGEPORT, CONNECTICUT, ASSIGNOR TO THE SMITH & EGGE M'F'G CO., OF BRIDGEPORT, CONNECTICUT, A CORPORATION OF CONNECTICUT.

PUNCH.

1,308,272.

Specification of Letters Patent.

Patented July 1, 1919.

Application filed March 29, 1918, Serial No. 225,426. Renewed May 20, 1919. Serial No. 298,547.

To all whom it may concern:

Be it known that I, JOHN L. BERGLUND, a citizen of the United States, residing at Bridgeport, Fairfield county, Connecticut, have invented certain new and useful Improvements in Punches; and I do declare the following to be a full, clear, and exact description of the invention, such as will enable others skilled in the art to which it appertains to make and use the same.

This invention relates to certain new and useful improvements in a punching tool and more particularly to the plier type in which a turret or hub is journaled on one of a pair of handles or levers and equipped with a peripheral series of radially disposed punches for selective operation upon the anvil that is carried on the other lever.

Means have heretofore been provided for holding the hub fixed in a predetermined position so that a selected punch will be disposed for striking upon the anvil when the hand levers are brought together, such means comprising a series of notches in the side face of the hub for engagement by a spring catch. In mounting the punches on the periphery of the hub it is essential that the periphery be most accurately drilled so as to locate the punches in direct alinement with the respective notches. This operation and method is exceedingly difficult because there are as many notches as there are punches and these are so correlated that they must be formed with the utmost accuracy.

The principal object of this invention is, therefore, to simplify the construction and at the same time to obtain great accuracy without such heretofore required difficult and expensive methods of manufacture.

The invention further resides in the features of construction and the arrangements and combinations of parts hereinafter described and claimed, the preferred embodiment being exemplified in the accompanying drawing wherein—

Figure 1 is a side elevation of the improved tool;

Fig. 2 is a longitudinal horizontal section on line 2—2 of Fig. 1; and

Fig. 3 is a detailed perspective view of the improved spring catch or lock.

As illustrated, the tool is of the plier type embodying pivotally connected handles or levers 1 normally urged apart by spring 2, and equipped at their forward ends with the

anvil 3 and turret or hub 4, respectively. The outer side face of the hub may be provided with the proper figures or characters for identifying the peripherally and radially disposed punches 5 which have cylindrical base portions 6 adjacent the periphery of the hub.

The hub-bearing lever 1 is offset so as to dispose the punches and anvil in a common plane, such offset forming a shoulder 7 in which one end of the spring catch 8 is fixed, as by removable screws 9. This leaf spring 8 is extended out alongside the hub and has a lateral wing 10 bent at right angles over the periphery of the hub. A notch or concave seat 11 is formed in the edge of the lateral wing 10 to receive the individual punches, preferably the cylindrical base portions.

Thus, only one notch is required in the present construction, this being in the spring catch which is the only element that must be accurately located to bring the single notch in the exact true position with respect to the cutting anvil. It is to be noted that a very important feature resides in the fact that the notch centers on the punches themselves. No careful and accurate drilling of the holes in the hub periphery is necessitated, but the punches may be located at varying intervals and not with any particular reference to any other part of the punch. The hub may be rotated in either direction, and when the spring is engaged between two punches both will be held away from the anvil.

What is claimed is:

1. In a punching tool, a pair of levers pivotally connected to provide handle portions and jaw portions, an anvil carried by one of the jaws, a hub journaled on the other jaw, radially extending punches fixed on the periphery of the hub for selective co-operation with the anvil when the jaws are closed, and a spring catch secured to the jaw which carries the hub and provided with a notch which is in direct alinement with the anvil when the jaws are in closed position, said notch being in the path of the punch bases when the hub is revolved, whereby the punches will engage with the notch and thereby be in direct alinement with the anvil.

2. In a punching tool, a pair of levers pivotally connected to provide handle por-

tions and jaw portions, an anvil carried by one of the jaws, a hub journaled on the other jaw, radially extending punches fixed on the periphery of the hub for selective coöperation with the anvil, each punch having a substantially similar and cylindrical base portion adjacent the hub, and a leaf spring catch secured at one end to the jaw which carries the hub and having its opposite end 10 extended alongside the hub with a lateral wing bent over the periphery of the hub,

15 said wing being formed with a notch for receiving the base portions of the punches and holding the selected punch operative relative to the anvil.

In testimony whereof I affix my signature in presence of two witnesses.

JOHN L. BERGLUND.

Witnesses:

F. W. SMITH,
M. T. LONGDEN.
